EDWIN E. BARNEY, OF ILLION, NEW YORK, ASSIGNOR TO REMINGTON TYPEWRITER COMPANY, OF ILLION, NEW YORK, A CORPORATION OF NEW YORK.

TYPE-WRITING MACHINE.

1,247,920.

Specification of Letters Patent. Patented Nov. 27, 1917.

Application filed August 17, 1917. Serial No. 186,713.

To all whom it may concern:

Be it known that I, EDWIN E. BARNEY, citizen of the United States, and resident of Ilion, in the county of Herkimer and State of New York, have invented certain new and useful Improvements in Type-Writing Machines, of which the following is a specification.

My invention relates to typewriting machines and more particularly to tabulating mechanism.

The main object of my invention, generally stated, is to provide simple and effective means to aid in setting stops by hand on a stop bar so that they may be rapidly and accurately positioned without the necessity of resorting to the use of a scale.

To the above and other ends which will hereinafter appear my invention consists in the features of construction, arrangements of parts and combinations of devices set forth in the following description and particularly pointed out in the appended claims.

In the accompanying drawings, wherein like reference characters represent corresponding parts in the various views,

Figure 1 is a fragmentary side elevation with parts in section of only so much of a typewriting machine as is necessary to illustrate my invention.

Fig. 2 is a detail perspective view of a sheet metal bracket, which forms a support for the stop setting gage or guide of my invention.

Fig. 3 is a fragmentary plan view of a part represented in Fig. 1.

Fig. 4 is a detail perspective view of the stop setting gage or device.

Heretofore in setting column stops by hand it has been customary for the operator to first determine with reference to an ordinary carriage scale just where each column stop is to be located and then to set the column stops at corresponding points on the stop bar with the aid of a scale thereon which corresponds to the carriage scale.

This is a slow, tedious and unsatisfactory method that often results in the column stops being improperly placed and in some

instances the improper setting of the stops may not be observed until the work has been spoiled. By my present invention I overcome these disadvantages and provide a director or guide with the aid of which each stop may be set by hand on the stop bar without resorting to the use of a scale and with the assurance that each stop will be properly positioned with mechanical accuracy, as will hereinafter appear.

In the present instance I have embodied my invention in a No. 10 Remington machine, which is equipped with a column selector like that disclosed in the patent to George A. Seib, No. 1,132,286, dated March 16, 1915, but have only shown so much of that machine as may be necessary to arrive at an understanding of my invention. It should be understood, however, that the invention may be embodied in various other styles of typewriting machines, and wherever it may be found available as an aid in properly placing stops on a stop bar.

In the No. 10 Remington machine the tabulator rack or column stop bar 1 is carried by and travels with the carriage and for the purposes of the present case this stop bar may be regarded as a part of the carriage. The toothed bar 1 is provided with interdental spaces 2 located at letter space intervals throughout its length to provide individual attaching means by which each plate-like bifurcated column stop 3 may be connected with the bar at different points in the length thereof. Each stop has the usual retaining spring 4 which engages the bar when the stop is introduced in place in an interdental space therein, thus holding the stop against accidental detachment from the bar. In the present instance each stop is shown provided with a contact portion 5, the contact portions on different stops traveling in different paths.

Cooperative key controlled selecting stops 6 are arranged at different elevations where each may be projected in the path only of the stop or stops 3 which have their contact portions 5 at the same elevation as the projected key controlled stop. The stops 6 are pivoted in a frame 7, which is secured

to the frame of the machine and for the purposes of the present case may be regarded as a part thereof.

The parts thus far described are constructed like the corresponding parts in the No. 10 Remington machine, equipped with the Seib invention; although for the purpose of my present invention any suitable column stop or tabulator stop mechanism may be employed.

A sheet metal bracket, designated as a whole by the reference numeral 8, may be formed as indicated in Fig. 2 and as thus constructed is adapted to embrace the upper portion of the tabulator frame 7 as represented in Figs. 1 and 3. Each side 9 of the bracket is perforated at 10 for the reception of the stem of a headed screw 11 by which the bracket is secured to the tabulator frame or housing 7. The front of the bracket 8 is open or apertured at 12 for the free passage therethrough of the selecting stops 6. Upwardly projecting ears 13 extend from the bracket 8, said ears being turned at their ends to form bearings 14 to receive and hold a pivot pin 15. A plate-like guide, designated as a whole by the reference numeral 16, and preferably made of sheet metal, is formed with downwardly projecting perforated ears 17 by which it is mounted on the pivot pin 15 between the ears 13. A coiled spring 18 surrounds the pin 15 and bears at one end, as at 19, against the guide and forward of the pivot 15 thereof. The opposite end of the spring bears against the front of the bracket 8 so that the force of the spring is exerted to move the guide to and hold it normally in the upper full-line position shown in Fig. 1. From an inspection of this figure it will be seen that the rear end 20 of the guide bears on the top of the housing 7, and limits the movement of the guide under the action of its spring. The forward end of the device is apertured or slotted at 21, the width of the slot being slightly greater than the thickness of the stop 3 and its spring 4. When the guide is in the normal position, shown in full lines in Fig. 1, it is out of co-operative relation with the stop bar and the column stops carried thereby and does not interfere with the operation of the tabulator.

In the No. 10 Remington machine the stop bar 1 is adapted to be turned on its longitudinal axis from the position shown in Fig. 1 to that indicated in Fig. 3, where the teeth on the stop bar extend vertically. This is to facilitate the attachment or resetting of the stops.

Let it be assumed that a resetting is desired; that the bar has been turned to the position shown in Fig. 3, and that the stops have been removed. The operator may then introduce a work sheet into the machine.

The work sheets are ordinarily ruled with vertical lines to determine the different columns. After such a sheet, or a previously prepared dummy sheet indicating where the different columns are to come on the sheet, has been introduced into the machine, the carriage is moved along until the point on the sheet where the first of the series of columns is to begin is at the printing point. A printing point indicator is usually employed to aid in thus positioning the carriage. The guide is then turned from the full-line to the dotted line position shown in Fig. 1 and the slot 21 in the guide will be brought into register with the pair of oppositely disposed spaces 2 in the stop bar, the body of the guide covering the spaces on either side of those which are in register with the opening 21. The operator then inserts a stop 3 through the opening 21 into the only space 2 in the bar in which the stop can be received at this time. From an inspection of Fig. 3 it will be seen that the opening 21 in the guide is just to the right of the abrupt engaging faces 6^a of the series of key-actuated stops 6. Therefore, each stop 3 placed on the bar with the aid of the guide 16 will subsequently co-operate with its associated key controlled projected stop 6 whenever the carriage reaches the point where the stop was introduced through the guide. After the first stop 3 is in place the guide is released and is returned by its spring to normal position. The operator then moves the carriage along until the beginning of the second column reaches the printing point. The guide is then moved to effective or operative position and a second stop 3 is introduced as before. And so on the stops are placed in position on the bar one after another until the requisite number are in place; then the bar is turned back to the operative position shown in Fig. 1.

The device 16 serves to guide the eye and the hand of the operator immediately to the place at which the tabulator stop is to be located and then serves to aid the operator in the placement or attachment of the stop on the bar.

The prongs 21^a on either side of the slot 21 may be of a width to cover one or more pairs of registering kerfs to the right and left of the selected pair into which the stop is about to be inserted, thus making it much easier or less confusing for the operator in the act of setting the stops. Although I have shown and prefer a stop-bar comprising two rows of teeth with spaces therebetween it will be understood that different forms or constructions of stop-bars may be used instead. Likewise other detail construction of tabulator stops may be employed in lieu of that herein illustrated and preferred.

From the foregoing description it will be understood that the guide 16 is carried by a fixed portion of the machine and bears a definite relation to the key projected stops 5 and to the printing point, and as the carriage arrives in the proper position, automatically indicates or denotes to the operator the position where the stop is to be placed and also acts as a gage or guide for the operator in hand positioning the stops on the relatively movable stop bar.

It will be understood that in the event of the stop bar being carried by the frame of the machine the guide or gage will be carried by the carriage. In either event one of these members is carried by the carriage and the other by the frame of the machine and there is a relative movement between the stop bar and the guide.

What I claim as new and desire to secure by Letters Patent, is:—

1. In a typewriting machine, the combination of a stop bar, stops attachable by hand to said bar at different points along the same, and a guide separate and distinct from the bar to aid in the hand positioning of said stops on the bar.

2. In a typewriting machine, the combination of a stop bar, stops attachable by hand to said bar at different points along the same, and a guide movable into and out of coöperative relation with said bar to aid in the hand positioning of said stops on the bar.

3. In a typewriting machine, the combination of a stop bar, stops attachable by hand to said bar at different points along the same, and a guide separate and distinct from the bar to aid in the hand positioning of said stops on the bar, one of said bar and guide parts being carried by the frame of the machine and the other by the carriage so that one is moved relatively to the other during the travel of the carriage.

4. In a typewriting machine, the combination of a stop bar, stops attachable by hand to said bar at different points along the same, and a mechanical device separate and distinct from the stops and stop bar and which denotes to the operator the position on the stop bar where a stop is to be attached by hand.

5. In a typewriting machine, the combination of a stop bar, stops attachable by hand to said bar at different points along the same, a device which denotes the position on the stop bar where a stop is to be attached by hand, and means which enable said device to be moved into and out of coöperative relation with said bar.

6. In a typewriting machine, the combination of a stop bar provided with stop attaching means at letter space intervals, and a guide movable into and out of register with

each individual attaching means on the stop 65 bar to indicate the point where a stop is to be attached to the bar by hand; said guide bearing a definite relation to the printing point.

7. In a typewriting machine, the combination of a stop bar provided with interdental spaces at letter space intervals, and a guide having an aperture adapted to register successively with each interdental space in the stop bar and through which a stop may be 75 introduced by hand into the interdental space with which the aperture in the guide is in register.

8. In a typewriting machine, the combination of a stop bar provided with interdental 80 spaces at letter space intervals, and a guide having an aperture adapted to register successively with each interdental space in the stop bar and through which a stop may be introduced by hand into the interdental 85 space with which the aperture in the guide is in register, one of said guide and bar members being carried by the frame of the machine and the other by the carriage, and the guide being mounted for movement into 90 and out of coöperative guiding relation with said bar.

9. In a typewriting machine, the combination of a movable stop bar having attaching means at letter space intervals, stops attached by hand to said bar, and a spring-pressed guide carried by a fixed part of the machine and having a guiding portion which is adapted to register successively with each individual attaching means on the stop bar and to guide a stop inserted by hand to the registering attaching means on the bar, the spring for said guide normally maintaining it out of coöperative relation with the bar 100 and the stops thereon.

10. In a typewriting machine, the combination of a stop bar having interdental spaces therein at letter space intervals, and a plate having an aperture therein through which a stop may be introduced by hand into the registering interdental space in the bar, one of said plate and bar members being carried by a fixed part of the machine and the other traveling with the carriage.

11. In a tabulator mechanism, the combination of a stop bar, and a guiding device to assist in the placement of stops by hand on said bar, said guiding device being movable into and out of coöperative relation with said stop bar.

12. In a tabulator mechanism, the combination of a stop bar and a hinged and spring-pressed guide for assisting in the placement of stops on said stop bar.

13. The combination of a stop bar and a guide movable toward and away from said bar and slotted for the passage therethrough of stops to be mounted on said stop bar.

14. The combination of a stop bar having a series of kerfs at letter space distances apart, and a guide having a slot to register with a selected kerf in the stop bar and having cover portions for the kerfs adjacent to said selected kerf, said guide being movable directly by hand into and out of co-operative relation with said stop bar.

Signed at Ilion, in the county of Herkimer, and State of New York this 14th day of 10 August, A. D. 1917.

EDWIN E. BARNEY.
